[57] CLAIM

The ornamental design for a paint scheme for an aerostar aircraft, as shown.

DESCRIPTION

FIG. 1 is a perspective view from the right rear of a paint scheme for an aerostar aircraft showing my new design;

FIG. 2 is a side perspective view from the left front thereof;

FIG. 3 is a front view thereof;

FIG. 4 is a bottom plan view thereof;

FIG. 5 is a left side elevational view thereof;

FIG. 6 is an enlargement of the circled portion 6 of FIG. 5 and is typical of all striping on the aircraft; and,

FIG. 7 is an enlargement of the encircled portion 7 of FIG. 5 and is typical of the shading of characters of the identification number of the aircraft.
